US00D363288S

United States Patent [19]

Brehmer et al.

[11] Patent Number: Des. 363,288

[45] Date of Patent: **Oct. 17, 1995

[54] MICROWAVE ANTENNA REFLECTOR

[75] Inventors: **Todd G. Brehmer**, San Jose; **Albert W. Berg**, Newark; **Allen F. Podell**, Palo Alto; **John M. Wachsman**, Pleasanton; **Laurence M. Markowitz**, deceased, late of Menlo Park, all of Calif., by Susan L. Markowitz, legal representative

[73] Assignee: **Pacific Monolithics, Inc.**, Sunnyvale, Calif.

[**] Term: **14 Years**

[21] Appl. No.: **14,008**

[22] Filed: **Oct. 8, 1993**

[52] U.S. Cl. **D14/230**; D14/231

[58] Field of Search .... D14/230, 234, D14/236; 343/720, 761, 781 R, 900, 901, 907, 908, 912
